UNITED STATES PATENT OFFICE.

LOUIS AUGUSTE CHARLES, OF LEVALLOIS, FRANCE.

DRIVE FOR THE DISTRIBUTION-GEAR OF INTERNAL-COMBUSTION ENGINES.

1,334,988.

Specification of Letters Patent. Patented Mar. 30, 1920.

Application filed September 4, 1919. Serial No. 321,618.

To all whom it may concern:

Be it known that I, LOUIS AUGUSTE CHARLES, a citizen of the French Republic, residing at No. 18 Rue Fazilleau, Levallois, France, have invented certain new and useful Improvements in Drives for the Distribution-Gear of Internal-Combustion Engines, of which the following is a specification.

This invention has for its object to provide a universal drive for the distributing gear of internal combustion engines. The improved gear drive comprises a cam shaft rotated by the engine with, for each cylinder, an admission cam, an exhaust cam, a compression-relieving cam, and two cams of variable shapes for admitting the fuel and the injection air.

This cam shaft may be shifted longitudinally along its axis so that this shifting shall bring simultaneously under the rockers of the valves and the injection needle-valves, different "concordant" sections of the cams corresponding to the various speeds of the engine.

The operation of this cam shaft will allow of effecting in a very simple manner all the operations of the engine and all the adjustments in the admission of the fuel and the injection air. Special devices hereinafter described allow of producing the stoppage and the starting of the engine by the same shifting movement.

The accompanying drawings illustrate by way of example a constructional form of the improved drive applied to an engine of the Diesel type, wherein the admission of the fuel and the injection air is effected by means of two needle-valves as in the engine described in the present applicant's earlier application filed April 26th, 1919, and bearing Serial No. 293,040, entitled "An improved injector for internal combustion engines of the Diesel type." In these drawings:

Figure 1 is a general view of the universal drive for the distributing gear of the engine.

Figs. 2 and 3 are detailed views of the mechanism for effecting the longitudinal shifting of the cam shaft.

As shown, 1 is the cam shaft mounted in bearings 2 and 3. This shaft carries a toothed wheel 4 driven by a pinion 5 that receives its motion from the engine. The shaft 1 carries the various cams that serve to operate all the parts for the admission,

exhaust, and for the injection of the fuel into the engine, namely:—the cam 6 for admitting pure air, which through the medium of the rocker 7 pivoted on the axle 8, actuates the pure air admission valve of the engine; the exhaust cam 9 for actuating the exhaust valve through the medium of the rocker 10 pivoted on the same axle 8; the injection cam 11 which through the medium of the rocker 12, actuates the needle valve for injecting the compressed air; the fuel-admission cam 13 which through the medium of the rocker 14 actuates the fuel-admission needle valve; the two last cams 15 are cams of varying shape, and their different sections which are simultaneously in engagement with their rockers are "concordant", that is to say, they correspond to a determined speed of running of the engine. Consequently by shifting the shaft 1 in this axial direction, all the various speeds of this engine will be produced.

The air-admission cam 11, and the fuel-admission cam 13, are each prolonged beyond the lowest portions of their inclined sections by a cylindrical section 15 which corresponds to the rest-positions of the air-injecting and fuel-injecting needle valves. By bringing these cylindrical sections under the rockers 12 and 14, the engine is stopped. The exhaust cam 9 is provided with a nib 9' the function of which is hereinafter described.

The drive (Fig. 2) for effecting the longitudinal shifting of the cam shaft 1, is constituted as follows:—

The cam shaft 1 is terminated at its left end in shoulders or collars mounted in a ball thrust bearing 16, the cage of which consists of a sleeve 17 whose outer surface formed with grooves 18 constitutes a screw working in a nut 19 connected to the frame of the engine by means of a feather key 20.

The screw 17 is prolonged at its left end by a cylindrical portion 21 formed with longitudinal grooves 22 in which the toothed wheel 23 is engaged by means of its hub. The wheel 23 meshes with a worm 24 driven by a hand wheel 25.

The shaft 1 is prolonged at its left end by a stem 26 (Fig. 3) fitted in a socket 27. In the prolongation of this stem 26 there is situated a stud 28 whose end bears, during a certain part of the shifting movement of the cam shaft 1, against a valve 29 arranged in the pipe 30 that communicates with a

compressed air reservoir. This valve is kept constantly compressed against its side by the pressure of the air and of a spring 31. This valve 29 is adapted to establish communication between the pipe 30 and the box 32 of a rotary distributor 33, which thus controls the admission of the compressed air into the engine.

- The operation of the drive for displacing the cam shaft is as follows:—The actuation of the hand wheel 25 produces, through the medium of the worm 24, rotation of the worm wheel 23, and thus causes, through the grooves 22, rotation of the sleeve 17 that acts as a screw by reason of its helical grooves 18, working in the fixed nut 19, whereby the sleeve 17 is caused to move longitudinally, in which movement it carries with it the cam shaft 1.
- 20 The toothed wheel 4 serving to rotate this cam shaft by means of the pinion 5, is likewise mounted on the shaft by means of longitudinal grooves that allow the said shaft to move, while the toothed wheel 4 remains 25 fixed between ball bearings.

The longitudinal shifting of the cam shaft 1 as above described allows of variations of speed of the engine and of its stoppage when the rockers 12 and 14 come to 30 bear upon the cylindrical portions 15 of the fuel-admission cam 13 and air-admission cam 11.

When the cam shaft is in this position, then in order to start the engine it is sufficient to shift said shaft toward the left for a distance sufficient to enable the stud 28 to 35 open the valve 29. The compressed air reservoir is thus placed in communication with the engine, and the rotary distributor 40 33 then admits compressed air into the engine at the desired point of the stroke of the pistons in each cylinder, so as to start the engine.

The compression-relieving nib 9' of the 45 exhaust cam 9 is situated under the roller 10, and the engine will work by the action of the compressed air without any compression in the cylinders.

The cam shaft is then returned toward the 50 right, so that the valve 29 is closed thereby. Then immediately after the starting and immediately before the rockers 12 and 14 actuating the fuel needle valve and the injection air needle valve, reach their operating 55 inclines, and the normal working of the engine is able to continue, the nib 9' escapes from the rocker 10, and the engine continues to revolve by the momentum of its rotational motion, but this time with compression in 60 the cylinders.

These successive compressions of pure air have the result of heating the cylinders, vaporizing the water mist that has settled on their inside surfaces by the expansion of 65 the starting air, and likewise of heating the

mixture of pure compressed air delivered into each cylinder by the residual hot air that has remained therein after each exhaust.

Owing to these heatings, the fuel on entering the engine will find awaiting it a heated medium that will facilitate the ignition of the said fuel. Therefore, as above stated, it is possible to cause the engine to run at all speeds, the injection air and the fuel being 75 suitably proportioned, owing to the "concordance" of the sections of the cams of varying shapes which come simultaneously into operation.

When it is desired to regulate the engine 80 to run at uniform speed, an automatic governor driven by the engine may be caused to act upon the hand wheel 25. This governor will have the effect of shifting automatically the shaft 1 in the requisite direction for 85 causing the speed to resume the determined rate irrespectively of the load on the engine. A safety governor may likewise be provided in connection with the hand wheel 25, for the purpose of limiting the speed to a maximum 90 in the case of a sudden drop in the resistance of the driven machine or vehicle.

This case is more particularly useful for ships, in order to prevent the engine from racing when the screw propeller is lifted out 95 of the water owing to the pitching of the ship.

What I claim is:—

1. In a universal distribution gear drive for internal combustion engines, the combination of an axially movable cam shaft rotated by the engine, having fixed upon it an air admission valve actuating cam of uniform shape, an exhaust cam of uniform shape, a fuel admission cam of varying 100 shape, and an injection air admission cam of varying shape, these four cams actuating four rockers; these rockers operating respectively the air admission, exhaust, fuel admission and the injection needle valves 105 of the engine, the sections of the varying shape cams that come simultaneously into engagement with their respective rockers being "concordant," that is to say, they correspond to a determined speed of rotation 110 of the engine.

2. In a universal distribution gear drive for internal combustion engines, the combination of an axially movable cam shaft rotated by the engine, having fixed upon it an air admission valve actuating cam of uniform shape, an exhaust cam of uniform shape, a fuel admission cam of varying shape, and an injection air admission cam of varying 115 shape, these four cams actuating four 120 rockers; these rockers operating respectively the air admission, exhaust, fuel admission and the injection needle valves of the engine; the varying shape cams comprising after the lowest portions of their inclined 125 130

sections, cylindrical sections that correspond to the stoppage of the engine; the sections of the said varying shape cams that come simultaneously into engagement with their 5 respective rockers, being "concordant."

3. In a universal distribution gear drive for internal combustion engines, the combination of an axially movable cam shaft rotated by the engine; a finger at the end of 10 said shaft; a starting valve operated by said finger for admitting compressed air for starting the engine; said cam shaft having fixed on it an air admission valve actuating cam of uniform shape, an exhaust cam of uniform 15 shape, a fuel admission cam of varying shape and an injection air admission cam of varying shape; these four cams actuating four rockers, said rockers operating respectively the air admission, exhaust, fuel 20 admission and the injection needle valves of the engine; the varying shape cams comprising after the lowest portions of their inclined sections cylindrical sections that correspond to the stoppage of the engine; the 25 sections of the said varying shaft cams that come simultaneously into engagement with their respective rockers being "concordant."

4. In a universal distribution gear drive for internal combustion engines, the combination of an axially movable cam shaft rotated by the engine; a finger at the end of 30 said shaft; a starting valve operated by said finger for admitting compressed air for starting the engine; said cam shaft having fixed on it an air admission valve actuating cam of universal shape, an exhaust cam of uniform shape, a fuel admission cam of varying shape and an injection air admission cam of varying shape; these four 35 cams actuating four rockers, said rockers operating respectively the air admission, exhaust, fuel admission and the injection needle valves of the engine; the varying shape cams comprising after the lowest portions of their inclined sections, cylindrical sections 40 corresponding to the stoppage of the engine; the sections of the said varying shape cams that come simultaneously into engagement with their respective rockers being "concordant."

45 5. In a universal distribution gear drive for internal combustion engines, the combination of an axially movable cam shaft rotated by the engine, collars on the end of 50 said cam shaft, a ball thrust bearing engaging said collars, a screw-shaped sleeve fixed to the cage of said ball thrust bearing, a fixed nut meshing with said sleeve, grooves 55 parallel to the axis on the end of said sleeve; a worm wheel engaging said grooves; a worm driving said worm wheel; a hand wheel actuating said worm; a finger fixed on the end of said cam shaft; a starting valve 60 operated by said finger for admitting compressed air for starting the engine; said cam shaft having fixed on it an air admission valve actuating cam of universal shape, an exhaust cam of uniform shape, a fuel admission cam of varying shape and an injection air admission cam of varying shape; these four 65 cams actuating four rockers, said rockers operating respectively the air admission, exhaust, fuel admission and the injection needle valves of the engine; a nib on said

actuating said worm; said cam shaft having fixed on it an air admission valve actuating cam of uniform shape, an exhaust cam of uniform shape, a fuel admission cam of varying shape, and an injection air admission cam of varying shape; these four cams actuating four rockers, said rockers operating respectively the air admission, exhaust, fuel admission and the injection needle valves of the engine; the sections of said 70 varying shape cams that come simultaneously into engagement with their respective rockers being "concordant."

6. In a universal distribution gear drive for internal combustion engines, the combination of an axially movable cam shaft rotated by the engine, collars on the end of 75 said cam shaft, a ball thrust bearing engaging said collars, a screw-shaped sleeve fixed to the cage of said ball thrust bearing, a fixed nut meshing with said sleeve, grooves 80 parallel to the axis on the end of said sleeve; a worm wheel engaging said grooves; a worm driving said worm wheel; a hand wheel actuating said worm; said cam shaft 85 having fixed on it an air admission valve actuating cam of uniform shape, an exhaust cam of uniform shape, a fuel admission cam of varying shape and an injection air admission cam of varying shape; these four 90 cams actuating four rockers, said rockers operating respectively the air admission, exhaust, fuel admission and the injection needle valves of the engine; the varying 95 shape cams comprising after the lowest portions of their inclined sections, cylindrical sections corresponding to the stoppage of the engine; the sections of the said varying shape cams that come simultaneously into engagement with their respective rockers 100 being "concordant".

7. In a universal distribution gear drive for internal combustion engines, the combination of an axially movable cam shaft rotated by the engine, collars on the end of 105 said cam shaft, a ball thrust bearing engaging said collars, a screw-shaped sleeve fixed to the cage of said ball thrust bearing, a fixed nut meshing with said sleeve, grooves 110 parallel to the axis on the end of said sleeve; a worm wheel engaging said grooves; a worm driving said worm wheel; a hand wheel actuating said worm; a finger fixed on the end of said cam shaft; a starting valve 115 operated by said finger for admitting compressed air for starting the engine; said cam shaft having fixed on it an air admission valve actuating cam of universal shape, an exhaust cam of uniform shape, a fuel admission cam of varying shape and an injection air admission cam of varying shape; these four 120 cams actuating four rockers, said rockers operating respectively the air admission, exhaust, fuel admission and the injection needle valves of the engine; a nib on said 125

130

exhaust valve cam for actuating the corresponding rocker for the position of the cam shaft that corresponds to the opening of the starting valve; the varying shape cams comprising after the lowest portions of their inclined sections, cylindrical sections that correspond to the stoppage of the engine; the sections of said varying shape cams that come simultaneously into engagement with 10 their respective rockers, being "concordant".

8. In a universal distribution gear drive for internal combustion engines, the combination of an axially movable cam shaft driven by the engine; collars on the end of 15 said shaft; a thrust ball bearing engaging said collars; a screw-shaped sleeve fixed to the cage of said ball thrust bearing; a fixed nut engaging with said screw sleeve; grooves parallel to the axis on the end of said sleeve; 20 a worm wheel engaging with said grooves; a worm driving said worm wheel; a hand wheel actuating said worm; an automatic governor driven by the engine acting upon said hand wheel; a finger fixed on the end 25 of said cam shaft; a starting valve oper-

ated by said finger for admitting compressed air for starting the engine; said cam shaft having fixed on it an air admission valve actuating cam of universal shape, an exhaust cam of uniform shape, a fuel 30 admission cam of varying shape and an injection air admission cam of varying shape; these four cams actuating four rockers, said rockers operating respectively the air admission, exhaust, fuel admission and the 35 injection needle valves of the engine; a nib on said exhaust valve cam for actuating the corresponding rocker for the position of the cam shaft that corresponds to the opening of the starting valve; the varying shape cams comprising after the lowest 40 portions of their inclined sections, cylindrical sections that correspond to the stoppage of the engine; the sections of said varying shape cams that come simultaneously 45 into engagement with their respective rockers, being "concordant".

In testimony whereof I have signed my name to this specification.

LOUIS AUGUSTE CHARLES.
